Primary Examiner—Celia A. Murphy*(74) Attorney, Agent, or Firm*—St. Onge Steward Johnston & Reens LLC(57) **CLAIM**

I claim the ornamental design for an outsole for a shoe, as shown and described.

DESCRIPTION

FIG. 1 is a bottom view of an outsole for a shoe showing my new design;

FIG. 2 is a bottom perspective view thereof;

FIG. 3 is a right side view thereof;

FIG. 4 is a left side view thereof;

FIG. 5 is a front view thereof;

FIG. 6 is a rear view thereof; and,

FIG. 7 is an enlarged cross sectional view taken along 7—7 of FIG. 1.

The broken line showing a shoe upper in FIGS. 1-6; along with the broken lines showing the interior surface in FIG. 7, represent the portions of the design that form no part of the claim.
